US00D819860S

(12) **United States Design Patent** (10) **Patent No.:** **US D819,860 S**
Clark (45) **Date of Patent:** **** Jun. 5, 2018**

(54) **LIGHT FIXTURE**

(71) Applicant: **3form, LLC**, Salt Lake City, UT (US)

(72) Inventor: **Bruce Clark**, Redmond, WA (US)

(73) Assignee: **3Form, LLC**, Salt Lake City, UT (US)

(**) Term: **15 Years**

(21) Appl. No.: **29/560,681**

(22) Filed: **Apr. 8, 2016**

(57) **CLAIM**

The ornamental design for a light fixture, as shown and described.

DESCRIPTION

FIG. 1 is a top perspective view of a light fixture;

FIG. 2 is a bottom perspective view thereof;

FIG. 3 is a top plan view thereof;

FIG. 4 is a bottom plan view thereof;

FIG. 5 is a front elevation view thereof; and,

FIG. 6 is a side elevation view thereof.

The broken lines depicted in FIGS. 1-6 illustrate portions of the light fixture that form no part of the claimed design.

1 Claim, 5 Drawing Sheets
